UNITED STATES PATENT OFFICE.

LAURA F. DAVIDSON, OF HOUSTON, TEXAS.

DESIGN FOR A TOY.

47,994.

Specification for Design.

Patented Oct. 19, 1915.

Application filed May 14, 1915. Serial No. 28,209. Term of patent 7 years.

To all whom it may concern:

Be it known that I, LAURA F. DAVIDSON, a citizen of the United States, residing at Houston, in the county of Harris and State of Texas, have invented a new, original, and ornamental Design for a Toy, of which the following is a specification, reference being had to the accompanying drawing, forming part thereof.

The figure is a perspective view of the toy, showing my new design.

I claim:

The ornamental design for a toy, as shown.

LAURA F. DAVIDSON.
